(57) **CLAIM**

The ornamental design for a electrical tool, as shown and described.

DESCRIPTION

FIG. 1 is a perspective view of an electrical tool showing one aspect of our new design;

FIG. 2 is a right side elevation view FIG. 1;

FIG. 3 is a left side elevation view FIG. 1;

FIG. 4 is a top plan view FIG. 1;

FIG. 5 is a bottom plan view FIG. 1;

FIG. 6 is a front elevation view FIG. 1; and,

FIG. 7 is a back elevation view FIG. 1.

The broken lines in the drawings depict portions of the electrical tool that form no part of the claimed design.
